Primary Examiner — Katrina A Betton(74) Attorney, Agent, or Firm — Boardman & Clark LLP(57) CLAIM

The ornamental design for an integrated tailgate liner and game apparatus, as shown and described.

DESCRIPTION

FIG. 1 is a plan view of the bottom side of an integrated truck tailgate liner and game apparatus according to the present invention;

FIG. 2 is a plan view of the top side of an integrated truck tailgate liner and game apparatus of FIG. 1, the left side being identical to that shown in the embodiment of FIG. 4, the right side being a mirror image of the left side;

FIG. 3 is a front side elevation view of FIG. 1, the rear side being identical to the front side elevation view of FIG. 3; and,

FIG. 4 is an isometric view of the top side, rear side and left side of an integrated truck tailgate liner and game apparatus according to the present invention, showing the left side shown in FIG. 1.

In the drawings, the broken lines depict portions of the article that form no part of the claimed design.

1 Claim, 2 Drawing Sheets(56)
